UNITED STATES PATENT OFFICE.

GUSTAVE DELAGE, OF PARIS, FRANCE, ASSIGNOR TO SOCIÉTÉ ANONYME NIEUPORT-ASTRA, OF ISSY-LES-MOULINEAUX, FRANCE, A CORPORATION OF FRANCE.

FLYING MACHINE MORE PARTICULARLY APPLICABLE TO FIGHTING MACHINES.

Application filed April 19, 1923. Serial No. 633,269.

To all whom it may concern:

Be it known that I, GUSTAVE DELAGE, a citizen of the French Republic, residing at 45 Rue Spontini, Paris, France, have invented 5 new and useful Improvements in Flying Machines More Particularly Applicable to Fighting Machines, of which the following is the specification.

The present invention has for its object 10 improvements in flying machines having a tractor propeller at the front. These improvements are characterized in that the seat of the pilot is arranged between the engine and the propeller, in front of the leading edge of the wings. This arrangement which is more particularly applicable to 15 fighting machines permits to increase the field of visibility of the pilot at the front, that is to say in the direction of the attack, and allows of arranging between the engine 20 and the propeller a firearm of large caliber firing through the hub of the latter. Other advantages resulting from this arrangement will be indicated in the following description 25 which is illustrated by way of example only in the accompanying drawing.

Fig. 1 shows in side elevation and partial sections an improved fighting machine in flight, according to the present invention.

Fig. 2 is a vertical section, on an enlarged scale, along the axis of the propeller hub and showing its driving reducing device.

The pilot's cock-pit is placed in the front part of the fuselage between the engine 1 35 and the propeller 2. The engine 1 is arranged below the wings 3 and rests upon an internal rib of the fuselage so that the distribution of the loads is effected in such a manner that the pilot can place himself in 40 front of the leading edges 3¹ of the wings 3, and that his visibility in the direction of advance of the machine is total.

The engine engages with the propeller 45 through the medium of an auxiliary shaft 4 which can be arranged parallel with the axis of rotation of the propeller, but which preferably drives the latter through the medium of a gear reducing device allowing the tubular propeller shaft 5 completely disengaged 50 so that the barrel 6 of a firearm of large

caliber or of a machine gun may be arranged through the bore thereof thus doing away with the synchronization mechanism necessary for firing through the propeller. The reducing device can be of any suitable 55 design; while two Cardan or universal joints are arranged at the points of junction 8 and 9 of the intermediate shaft 4 with the engine and the reducing device.

The reducer preferably comprises a casing 60 10 constructed in two parts assembled along the vertical plane, each of these parts 10 having lateral supports 11 for mounting on the forward portion of the fuselage. The case is also provided with superposed bores 65 or bearings the axes of which are parallel. The receiver bore is provided with roller bearings for the shaft 13 of a pinion 14 said shaft also carrying one of the elements of the universal joint 9. The other bore is fitted with roller bearings 15 and receives the hollow shaft 5, the interior of said shaft being of course engaged with the interior of the fire arm. This bearing 5 carries thereon by means of a key the second pinion 70 16 of the reducer which engages with the pinion 14 for completing the transmission of the movement. A double thrust ball bearing 7 supports the thrust of the propeller. It will be seen in view of the foregoing devices that should the ribs become deformed or should the fuselage become otherwise distorted and the motor drops, the intermediate shaft 4 is arranged at an inclined position without effecting a pull on 80 the shaft 5. In other words the reducer is not subjected to any course which would tend to change the position of the same especially the shaft 5 which would have a tendency to interfere with the use of the gun 85 90 the barrel of which is projected into the tubular shaft.

What I claim as my invention and desire to secure by Letters Patent is:—

In a combat plane in combination, a fuselage, a fire arm mounted therein, an engine mounted in the fuselage with its crank shaft beneath the fire arm, a tubular propeller shaft mounted in the forward part of the fuselage and through which the barrel of 100

the fire arm is arranged, a reducer mounted in the fuselage beneath and operably connected with the propeller shaft, an intermediate shaft having its ends universally connected with the reducer shaft and the engine shaft for transmitting movement from the engine to the reducer and at the

same time maintaining the propeller shaft in proper position even when the fuselage or other parts are subjected to distortion. 10 In testimony whereof I have signed my name to this specification.

GUSTAVE DELAGE.
